ARC CHUTE UTILIZING STAGGERED
U-SHAPED CONDUCTIVE MEMBERSCharles R. Peter, Wauwatosa, Wis., assignor to
Allis-Chalmers Manufacturing Company, Mil-
waukee, Wis.

Application July 3, 1950, Serial No. 171,843

4 Claims. (Cl. 200—144)

1

This invention relates in general to electric switching devices and in particular to electric arc extinguishing means for such switching devices.

It is a principal object of this invention to provide an improved arc extinguishing structure in which series connected arcs are successively drawn between a plurality of arc extinguishing members.

It is an additional object of this invention to provide an arc extinguishing structure in which series connected arcs are successively drawn and the series arcs are confined within a portion of the arc extinguishing structure.

Objects and advantages other than those outlined above will be readily apparent from the following detailed description when read in connection with the accompanying drawing, in which:

Fig. 1 is a side view of a switching device embodying the present invention;

Fig. 2 is an enlarged sectional view through the arc chute of the device illustrated in Fig. 1;

Fig. 3 is a sectional view taken along line III—III of Fig. 2; and

Fig. 4 is a development view looking in the direction of arrow IV of Fig. 2.

Referring to Fig. 1, a switching device embodying the present invention comprises a pair of relatively movable current carrying contacts 11, 12 between which an arc may be formed upon separation thereof. Contact 11 is connected through a curved conductive bar 13 to a terminal stud 14, while contact 12 is connected through a conductive member 15 and a flexible lead 16 to a terminal stud 17. Studs 14, 17 represent connections to a circuit which the device is to interrupt.

The fixed contact assembly is supported on a suitable insulating base 18 through stud 14. Secured to bar 13 is a U-shaped bridging member 28 of laminated magnetic material which cooperates in a well known manner with bar 13 to form a blowout assembly for impelling the arc formed upon separation of contacts 11, 12 into the arc extinguishing chute. This blowout assembly may be dispensed with if the heat generated by formation of the arc provides sufficient impelling force to blow the arc into the chute.

Contact 12 is movable into and out of engagement with contact 11 by movement imparted to a shaft 29. Shaft 29 is journaled in brackets 31 secured to base 18 by screws 32 and is given rotational movement by suitable actuating means (not shown) such as an electromagnet. Clockwise rotation of shaft 29 moves contact 12 in a clockwise direction from the position shown to

separate contacts 11, 12 and form an arc therebetween.

As shown in Figs. 2-4, the arc chute 41 comprises a pair of spaced side walls 42, 43 located on opposite sides of the path of movement of the arc. Chute 41 is provided with an intermediate section 44 adjacent contacts 11, 12 wherein the arc is formed and an exhaust section 45 between the top portions of side walls 42, 43. End members 46, 47 maintain the proper spacing between side walls 42, 43 and serve to confine the arc within the chute 41. The arc chute assembly is rigidly secured together by bolts 48 and nuts 49 extending through side walls 42, 43 and end members 46, 47.

An insulating member 51 is disposed midway between side walls 42, 43 and extends substantially parallel to walls 42, 43. Recesses 52, 53 are provided in end members 46, 47 respectively, to receive the ends of member 51. Two pluralities of U-shaped conductive members 54a through 54f and 55a through 55f are secured to side walls 42, 43 and form two rows disposed in the general lengthwise direction of the arc, the row of members 54 being staggered with respect to the row of members 55. Members 54, 55 may be made of any suitable heat resistant conductor such as steel or brass. As indicated on a representative conductive member 54f in Fig. 2, each conductive member 54 comprises a pair of spaced leg portions 56, 57 extending in the general direction of movement of the arc and a curved portion 58 joining leg portions 56, 57 in the intermediate section of the chute.

Members 54, 55 abut their respective side walls along an edge extending from the bight of the U to the exhaust section of the chute. Some of the conductive members 54, 55, and preferably all of them, increase in depth in a direction perpendicular to the direction of movement of the arc and to the lengthwise direction of the arc, i. e., away from the side walls to which they are secured and toward the insulating member 51, from the bight of the U, and are adjacent to or abut the insulating member 51 in the exhaust section of the chute. This increase in depth of members 54, 55 forms edges 61, as shown in Fig. 3, upon which the arc impinges during its movement in chute 41. As shown in the drawing, members 54, 55 may be set in recesses 62 in their respective side walls 42, 43, and if members 54, 55 abut insulating member 51 in the exhaust section of the chute, recesses 63 may be provided in member 51 to receive the abutting ends.

The arc chute assembly is detachably mounted

with respect to contacts 11, 12 by any suitable known means (not shown) to provide easy removal for replacement or repair.

Upon separation of contacts 11, 12, an arc is formed therebetween in the intermediate section 44 of chute 41. The heat generated by this arc impels the arc upwardly in the chute and the blowout assembly described above furnishes additional impelling force. The arc in moving upward first impinges on conductive member 55a between contact 11 and member 55a, and as contact 12 continues to move, the arc is extended until it impinges on member 55b. At this time the arc will exist in the form of a short arc between contact 11 and member 55a, another short arc between adjacent leg portions of adjacent members 55a, 55b, and another short arc between member 55b and contact 12. Continued movement of contact 12 causes the arc to successively impinge on the succeeding conductive members 55c, 55d, 55e, 55f, thereby successively drawing a plurality of short arcs between adjacent leg portions of adjacent conductive members 55.

As these short arcs move toward the exhaust section of the chute, the distance between adjacent leg portions of adjacent members 55 increases, thereby progressively increasing the resistance of the air gaps through which the short arcs must travel and hence reducing the magnitude of the arc current and hastening the extinction of the arc. In addition, the arc current flowing in conductive members 55 meets a path of continually increasing resistance as the short arcs move in the chute, owing to the increasing distance in the conductive members through which the arc current must flow. This increasing resistance further progressively reduces the arc current and thereby further speeds the extinction of the arc.

The plurality of short arcs continue to travel in chute 41, encountering paths of progressively increasing resistance, until the arcs are extinguished in the exhaust section of the chute.

Although in the above described operation of the arc chute, it was assumed that the arc impinged on member 55a upon separation of contacts 11, 12, it will be readily apparent that the arc might impinge on member 54a upon separation of the contacts and then be caused to successively impinge on members 54b, 54c, 54d, 54e, 54f, without changing the principle of operation of the arc extinguishing means.

Insulating member 51 serves to separate members 54 from members 55 and thereby confine the short arcs between either adjacent members 54 or adjacent members 55.

Members 54 are staggered with respect to members 55 to provide a maximum arc extinguishing effect regardless of the size of the arc current. When the interrupted current is of sufficient magnitude, the resultant arc will produce a region of conductive gas extending around insulating member 51 and in contact with both rows of members 54, 55. If members 54, 55 were aligned with each other, there would be no increase in the number of series arcs obtained in the chute with a current of this magnitude with respect to the number of arcs obtained with smaller currents. However, when members 54, 55 are staggered with respect to each other, as shown, if the arc current is of sufficient magnitude to produce an arc extending between staggered members 54, 55, around member 51, the arc current must flow in a zigzag path between leg portion of members 54 and leg portions of members

55, thereby nearly doubling the number of series arcs with respect to the number of series arcs which would be available if members 54, 55 were aligned. Also, the staggered relation of members 54, 55 insures that there is no point throughout the length of the arc at which the arc does not encounter a U-shaped short circuiting member, 54, 55, thereby insuring that the arc impinges on a conductive member shortly after being drawn.

10 Although but two embodiments of the invention have been shown and described, it will be apparent to those skilled in the art that various modifications may be made therein without departing from the spirit of the invention or from 15 the scope of the appended claims.

It is claimed and desired to secure by Letters Patent:

1. Means for extinguishing an electric arc movable in a predetermined general direction 20 comprising an arc chute provided with a pair of spaced side walls located on opposite sides of the path of movement of said arc and having an intermediate section wherein said arc is formed and an exhaust section, an insulating member disposed between said side walls in said exhaust section and extending parallel to said side walls, and a plurality of U-shaped conductive members 25 on which different portions of said arc successively impinge, said members being secured to 30 said side walls and forming two rows disposed in the general lengthwise direction of said arc, the members of one of said rows being staggered in said lengthwise direction with respect to the members of the other of said rows, each said 35 conductive member comprising a pair of spaced leg portions extending in the general direction of movement of said arc and having a curved portion joining said leg portions in said intermediate section to form a U, the said conductive 40 members secured to one of said walls abutting said one wall in said intermediate section and increasing in depth from the bight of said U in a direction toward said insulating member and abutting said insulating member in the exhaust 45 section of said chute.

2. Means for extinguishing an electric arc movable in a predetermined general direction comprising an arc chute provided with a pair of spaced side walls located on opposite sides of the 50 path of movement of said arc and having an intermediate section wherein said arc is formed and an exhaust section, an insulating member disposed between said side walls in said exhaust section and extending parallel to said side walls, 55 and a plurality of U-shaped conductive members on which different portions of said arc successively impinge, said members being secured to said side walls and forming two rows disposed in the general lengthwise direction of said arc, 60 the members of one of said rows being staggered in said lengthwise direction with respect to the members of the other of said rows, each said conductive member comprising a pair of spaced leg portions extending in the general direction 65 of movement of said arc and having a curved portion joining said leg portions in said intermediate section to form a U, the said conductive members secured to one of said walls abutting said one wall in said intermediate section and increasing in depth from the bight of said U in a direction toward said insulating member.

3. Means for extinguishing an electric arc movable in a predetermined general direction comprising an arc chute provided with a pair of 70 spaced side walls located on opposite sides of the

path of movement of said arc and having an intermediate section wherein said arc is formed and an exhaust section, an insulating member disposed between said side walls in said exhaust section and extending parallel to said side walls, and a plurality of U-shaped conductive members on which different portions of said arc successively impinge, said members being secured to said side walls and forming two rows disposed in the general lengthwise direction of said arc, the members of one of said rows being staggered in said lengthwise direction with respect to the members of the other of said rows, each said conductive member comprising a pair of spaced leg portions extending in the general direction of movement of said arc and having a curved portion joining said leg portions in said intermediate section to form a U, each said conductive member abutting one of said side walls in said intermediate section and increasing in depth from the bight of said U in a direction toward said insulating member and abutting said insulating member in the exhaust section of said chute.

4. Means for extinguishing an electric arc movable in a predetermined general direction comprising an arc chute provided with a pair of spaced side walls located on opposite sides of the path of movement of said arc and having an intermediate section wherein said arc is formed and an exhaust section, an insulating member disposed midway between said side walls in said

exhaust section and extending parallel to said side walls, and a plurality of U-shaped conductive members on which different portions of said arc successively impinge, said members being secured to said side walls and forming two rows disposed in the general lengthwise direction of said arc, the members of one of said rows being staggered in said lengthwise direction with respect to the members of the other of said rows, each said conductive member comprising a pair of spaced leg portions extending in the general direction of movement of said arc and having a curved portion joining said leg portions in said intermediate section to form a U, each said conductive member abutting one of said side walls in said intermediate section and increasing in depth from the bight of said U in a direction toward said insulating member and abutting said insulating member in the exhaust section of said chute.
